United States Patent Office

Des. 213,424
Patented Mar. 4, 1969

213,424

BOTTLE

Richard L. Weckman, Perrysburg, Ohio, assignor to Owens-Illinois, Inc., Toledo, Ohio, a corporation of Ohio

Filed Mar. 4, 1968, Ser. No. 10,848

Term of patent 14 years

U.S. Cl. D9—149
Int. Cl. D9—01

FIG. 1

FIG. 2

FIGURE 1 is an elevational view of a bottle, showing my new design, the opposite side being the same in appearance as the side shown;

The characteristic features of the design reside in the portions shown in full lines.

I claim:

The ornamental design for a bottle, substantially as shown and described.
